UNITED STATES PATENT OFFICE.

FRANKLIN W. OEHRL, OF PHILADELPHIA, PENNSYLVANIA.

MACHINE FOR MAKING ORNAMENTAL ROPE OR CORD.

1,310,402.

Specification of Letters Patent. Patented July 15, 1919.

Substitute renewal for application Serial No. 65,640, renewed December 7, 1915. This application filed July 20, 1918. Serial No. 245,908.

To all whom it may concern:

Be it known that I, FRANKLIN W. OEHRL, a citizen of the United States, and a resident of Philadelphia, in the county of Philadelphia and State of Pennsylvania, have invented an Improvement in Machines for Making Ornamental Rope or Cord, of which the following is a specification.

My invention relates to improvements in machines or apparatus for the manufacture of ornamental rope or cord, and it has for one of its objects to provide a construction in which the spool or equivalent carrier for the inner binding thread is supported in a new and novel manner with respect to other parts of the machine or apparatus.

Other objects and advantages of my invention will be hereinafter referred to in the descriptive portion of this specification or will become apparent therefrom.

One form of a convenient embodiment of my machine or apparatus is illustrated in the accompanying drawings but it will be understood that changes in the details of construction or arrangement of the parts may be made within the scope of the claims without departing from the said invention.

In the drawings:—

Figure 1 is a longitudinal sectional elevation of a machine or apparatus embodying my invention;

Fig. 2 is an end elevation looking toward the right in Fig. 1;

Fig. 3 is a transverse section on the line 3—3 of Fig. 1; and

Fig. 4 is a longitudinal sectional elevation of a modified construction of machine, the rear end portion thereof being broken away.

Referring to the drawings:—

1 designates the base portion of a machine and 2, 3 and 4 designate supporting posts secured to and extending upwardly therefrom. The said posts are provided with openings 5, 6 and 7 in which a revoluble member 10 is revolvably supported. Revolution of the member 10 is effected by a gear 15 secured thereto by means of binding screws 160, only one of which is shown, such gear being driven by means not shown in the drawing.

16, 17 and 18 designate plugs or blocks secured in the revoluble member 10, the first and the last of which are located at the ends while the plug or block 17 is located intermediate the ends of the said revoluble

member in alinement with the upright supporting post 3. The said plugs or blocks are secured in position within the revoluble member 10 by means of screws 20, only one of which is shown in connection with each 60 of the said plugs or blocks.

The revoluble member 10 is held against longitudinal movement in its bearings in the supporting posts 2, 3 and 4 by means of a flange 21 upon the outer end of the block 65 18 which rests against the outer side of the supporting post 4 which flange coöperates with the flange 22 upon the gear 15 which is situated in contact with the opposing side of the said supporting post 4. 70

Holes 23 are provided in the plugs or blocks 17 and 18 which holes are coaxial with the axis of revolution of the revoluble member 10 and the said plugs or blocks 17 and 18. 75

An inner binding thread guide member 24 is supported in the said holes and is secured therein by means of a sleeve 25 secured thereon and which is situated in contact with the inner side of the plug or block 18. The 80 presence of the said sleeve prevents longitudinal movement of the said guide member to the right in Fig. 1. Movement of the said guide member 24 in the opposite direction is prevented by the hub of the gear wheel 26 which is secured to the said guide member upon the outside of and adjacent to the plug or block 18. The said guide member 24 also serves as a support for a detachable former 28 secured upon the outer 85 forward end thereof by means of a binding screw 30 which passes through a collar 32 and engages the forward end portion of the guide member 24. The inner binding thread 90 35 passes through a hole through the guide member 24 and through the former 28. 95

The former being secured to and supported upon the inner thread guide member 24 which in turn is supported upon the revoluble plugs or blocks 17 and 18 it follows 100 that the said former would rotate unless means should be provided for the prevention of such rotation.

It is necessary that the former should be made stationary and for this purpose I have 105 provided the gear mechanism illustrated in detail in Fig. 3 of the drawings, in which,— 40 designates a gear secured to a member 41 which serves as a guide for the ornamental loop threads of the rope or cord and which 110

while revolving with the revoluble member 10 is held against rotation on its own axis. The said member 41 is supported in openings 43 in the plugs or blocks 16, 17 and 18. 5 45 designates an intermediate gear rotatably mounted upon a pivot 46 secured to the plug 18. The said gear 45 also revolves with the revoluble member 10 around the axis of the said revoluble member. The gear 10 45 is in engagement with both the gears 26 and 40. The revoluble member 10 revolves in the direction indicated by the arrow 47 in Fig. 3 and as a result of the fact that the gear 40 is held stationary upon the guide 15 member 41, although being revolved around the gear 26, and as it is constantly changing its position with respect to the gear 45, being at times in horizontal alinement therewith, at other times in vertical alinement therewith, and at other times occupying intermediate positions with respect thereto, it causes rotation of the gear 45 to the left about its pivot 46.

By reason of the fact that the gear 45 25 meshes with the gear 26 it tends to rotate the latter to the right (having reference to Fig. 3) in consequence of which the rotation of the gear 26 and the parts 24 and 28 connected therewith with the revoluble member 20 10 on which they are carried, is prevented and the said gear and the parts connected thereto are held stationary.

The ornamental thread guide 41 is held against rotation on its own axis by means of 35 its connection with the upper end of a link 50 pivotally connected at 51 to a link 52 pivoted at 53 to the base of the machine. The ornamental binding threads 55 are supplied from a plurality of spools or equivalent carriers supported upon a rack at the rear of 40 the machine, the said spools and the rack being, however, omitted from the drawing.

60 designates an outer binding thread which is supported in operative relation to 45 the former 28 by means of a roller 61 which in addition to supporting the said binding thread also operates to control and feed the ornamental threads which have been wound upon the former 28 therefrom. The 50 inner and outer binding threads 35 and 60 are twisted together and are pulled and fed forwardly, that is toward the right having reference to Figs. 1 and 2, by means of a twisting device not illustrated.

55 Although the revoluble member 10 is shown as being hollow and being provided with plugs therein for the purpose stated, it will be understood that the construction of the said revoluble member may be varied 60 and changed in various ways without in any way affecting my invention.

Referring to Fig. 1, 70 designates a spool supported upon a rod or spindle 71 which is secured to and supported upon the plug or 65 block 16 at the rear of the revoluble member

10. The said rod 71 is secured upon the said plug or block 16 by means of nuts 72 and 73 the former being secured at the left hand side of Fig. 1 and being in contact with the outer side of the plug 16 while the latter is secured at the inner end of the said rod. 70

74 designates a washer situated between the spools 70 and the plug or block 16 and 75 75 designates a washer situated between the inner end of a friction spring 76 and the adjacent end of the spool 70. The friction spring 76 is located at the inner end of the rod 71 between the said washer 75 and the nut 73. The tension of the said spring may 80 be varied by varying the position of the nut 73.

The spool 70 containing the supply of inner binding thread 35 is located interiorly of and coaxially with the revoluble member 85 10. The binding thread is led from the said spool through eyes 80 upon the inside of the said revoluble member 10. The inner binding thread is so wound upon the said spool that the revolution of the member 10 causes 90 revolution of the said spool in the same direction and at the same speed as the said revoluble member in consequence of which the point at which the thread is taken from the spool is maintained in constant relation 95 to the ornamental thread guide 41 and the threads guided thereby.

In addition to the revolution of the spool caused by the revolution of the member 10 it is given an additional speed of revolution 100 due to the drawing forward of the binding thread 35 by the twister (not shown) as above stated.

The presence of the friction springs 76 prevents the spool from overrunning itself. 105

In order that the spool or carrier 70 may be removed for the purpose of placing a new spool upon the spindle 71 or for any other purpose, I have provided openings 81 in the revoluble member 10 only one of which is 110 shown. If preferred, but one opening may be provided or if the size of the revoluble member admit, the number of the openings may be increased.

Referring to Fig. 4 of the drawings, I 115 have shown a modified construction differing from Figs. 1 to 3 of the drawings only in the manner of mounting the spool which supports the inner binding thread.

In Fig. 4, 85 designates a spool upon 120 which the supply of the inner binding 86 is wound. The said spool is supported upon the inner projecting end 87 of the inner thread guide 24. The said spool is held upon the said inner thread guide by means 125 of a nut 88 having screw threaded connection with the inner rear end of the projecting portion 87. The inner binding thread 86 extends from the spool 85 through an opening 90 in a guide arm 91 which is in- 130

tegral with or otherwise connected to the nut 88. The said arm extends radially from said nut 88 and is then bent and extended along the side of and parallel with the spool 5 to a point preferably opposite the longitudinal central portion of the spool. However, the point of termination of the guide arm 91 may be varied as desired.

The said inner binding thread also extends 10 through eyes 92 formed upon the said guide arm 91.

93 designates a tension spring located between washers 94, one of which is seated against the adjacent end of the spool 85 15 and the other one of which is seated against the adjacent side of the plug or block 17.

The pressure of the spring against the spool holds it with more or less firmness against the washer 96 situated between an 20 end of the spool 85 and the nut 88 whereby the spool is prevented from rotation except as desired. Being supported upon the projecting portion 87 of the stationary guide 24 the spool 85 is not rotated except as the 25 binding thread 86 is drawn therefrom as it is pulled forward and twisted by the twister (not shown) in the manner already stated.

Openings 97 (only one of which is shown) 30 are provided in the revolute member 10 (as is described in connection with Fig. 1) by means of which the spool or carrier 85 may be removed for the purpose of replacing the same with another spool or for any other purpose.

35 In both forms of construction the spools are located interiorly of the revolute member 10 and are supported thereon and the spools are of a size and diameter to permit the ornamental thread guiding member 41 40 or the ornamental threads 55 to be revolved entirely around the same.

Having thus explained the nature of my 45 said invention and described some of the ways of making and using the same, although without attempting to set forth all of the forms in which it may be made or all the modes of its use, which I claim is:—

1. In a machine for making ornamental 50 rope or cord, the combination of means for supporting inner and outer binding threads in operative relation to each other, revolute means for coiling loops of thread around said inner binding thread, the thread for forming the said loops being supported and 55 guided by said revolute means, a carrier for said inner binding thread which carrier is of less diameter than the cylinder of revolution of the thread of which the said loops are formed and which carrier is situated inside of such cylinder of revolution 60 whereby the said thread for forming the loops is revolved around said carrier.

2. In a machine for making ornamental 65 rope or cord, the combination of means for supporting the inner and outer binding

threads in operative relation to each other, revolute means for supporting and guiding the thread for forming the loops around the inner binding thread the revolution of said means outlining a cylindrical surface, a 70 carrier for said inner binding thread of less diameter than said cylindrical surface and being supported inside of said surface and coaxially therewith, whereby the said supporting means carrying the thread for forming the said loops is revolved entirely around the said inner binding thread carrier. 75

3. In a machine for making ornamental rope or cord, the combination of means for supporting inner and outer binding threads 80 in operative relation to each other, a revolute member, means for supporting and guiding threads for forming loops, which means is supported upon the said revolute member parallel with the axis thereof and 85 at a point removed from the said axis, a carrier for the inner binding thread which carrier is supported interiorly of the said revolute member and coaxially therewith, and the radius of which carrier is less than 90 the distance from the axis of said revolute member to the said support and guide whereby the said support and guide revolve around the said carrier and around the said inner binding thread to coil the said loops around 95 the same.

4. In a machine for making ornamental 100 rope or cord, the combination of a revolute member, a stationary former supported thereby, means for supporting inner and outer binding threads in operative relation to said former, means supported upon the said revolute member for supporting and guiding threads which are adapted to be looped or coiled around the said former and around 105 the said inner binding thread, a carrier for the said inner binding thread which carrier is located interiorly of the said revolute member and the radius of which is less than the distance of said loop thread supporting 110 and guiding means from its axis of revolution, whereby the latter is revolved around the said carrier and around the said inner binding thread.

5. In a machine for making ornamental 115 rope or cord, the combination of a revolute member, inner thread guiding means supported upon the said revolute member coaxially therewith, said means having a former supported thereon, means supported 120 upon the said revolute member at a distance from the axis thereof for supporting and guiding threads which are adapted to be coiled around the said former, means interposed between the said last mentioned thread 125 guiding means and the inner thread guiding means for preventing revolution of the latter in unison with its supporting revolute member, an inner thread carrier or supporting member secured to the said revolute mem- 130

- ber and coaxially therewith, the radius of which is less than the distance between the axis of said revolute member and the means for supporting and guiding the thread which 5 is adapted to be coiled around the said former, whereby said means and the said thread are adapted to be revolved around the said carrier and around the inner binding thread.
6. In a machine for making ornamental 10 rope or cord, the combination of a revolute member, a stationary former, means for supporting inner and outer binding threads in operative relation to said former, guiding means upon the said revolute member at a 15 distance from the axis thereof, which means is adapted to guide and support threads which are adapted to be coiled around the said former, a revolute carrier for the inner binding thread which carrier is supported 20 interiorly and coaxially of the said revolute member and the radius of which carrier is less than the distance of the said guiding means from the axis of said revolute member, and means for drawing off the inner 25 binding thread and thereby causing revolution of the said carrier in unison with the said revolute member, the point of the said carrier from which the binding thread is removed being held in constant relation to the 30 said loop thread guiding means.
7. In a machine for making ornamental 35 rope or cord, the combination of a revolute member, a former supported thereby, a thread or strand guiding member also supported by the said revolute member and being in parallel relation to the axis thereof, and means for preventing rotation of the 40 said former.
8. In a machine for making ornamental 45 rope or cord, the combination of a revolute member, a former supported thereby and

being coaxial therewith, an inner binding thread carrier supported upon and interiorly of the said revolute member and a thread or strand guiding member also supported upon 45 the said revolute member in parallel relation to the same, and means interposed between the said thread or strand guiding member and the said former to prevent the rotation of the latter.

9. In a machine for making ornamental 50 rope or cord, the combination of a revolute member, a former supported in axial alignment with the said revolute member, and a thread or strand guiding member supported 55 eccentrically of and entirely upon and interiorly of the said revolute member.

10. In a machine for making ornamental 60 rope or cord, the combination of a revolute member, a former supported in axial alignment therewith, and a thread or strand guiding member supported eccentrically of and interiorly of the said revolute member in 65 parallel relation to the axis thereof, one end of the said thread or strand guiding member being in operative relation to said former.

11. In a machine for making ornamental 70 rope or cord, the combination of an ornamental thread guide, a guide for a binding thread, a single revolute support for the 75 said guides, a former carried upon the outer end of the said binding thread guide, means whereby the said ornamental thread guide is revolved around said binding thread guide and the said former, and means for supporting a second binding thread in operative relation to the said former.

In testimony that I claim the foregoing as my invention, I have hereunto signed my name this eighteenth day of July, A. D. 1918. 80

FRANKLIN W. OEHRLÉ.
